UNITED STATES PATENT OFFICE.

GEORGE F. FIELDS, OF PADUCAH, KENTUCKY.

RAILWAY-RAIL ANCHOR.

SPECIFICATION forming part of Letters Patent No. 790,354, dated May 23, 1905.

Application filed February 11, 1905. Serial No. 245,258.

To all whom it may concern:

Be it known that I, GEORGE F. FIELDS, a citizen of the United States, residing at Paducah, in the county of McCracken and State 5 of Kentucky, have invented a new and useful Railway-Rail Anchor, of which the following is a specification.

This invention relates to devices for coupling or anchoring a block or fall or single or 10 double line hitch to a railway-track rail for use in clearing up wrecks or for other purposes where it is desired to make connection for any purpose to a railway-track, and has for its object to simplify and improve the construction of devices of this character.

With these and other objects in view, which will appear as the nature of the invention is better understood, the same consists in certain novel features of construction, as 15 hereinafter fully described and claimed.

In the accompanying drawings, forming a part of this specification, and in which corresponding parts are denoted by like designating characters, is illustrated the preferred 20 form of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

In the drawings thus employed, Figure 1 25 is a side elevation showing the device of the invention applied to a rail in position for operation and showing tackle connected therewith. Fig. 2 is a transverse sectional view taken through the device applied to the rail 30 and showing the link in a raised position.

The improved device comprises two plates 10 11, having recesses in their lower adjacent portions conforming to and closely embracing the opposite sides of the ball or tread, 15 vertical web, and tie-flange of a railway-rail 12 and with the portions above the rail provided with transverse apertures 13 14 for loosely receiving an endless pull-link 15. The upwardly-extended portions of the plates 20 are further connected by transverse clamp-

bolts 16 17, disposed near the ends of the plates and provided with nuts 18 19, preferably with operating-levers 20 21.

The device is disposed upon the rail at one of the joints and in engagement with the 55 clamp-plates forming the same, (represented at 22 23,) the latter acting as stops to prevent longitudinal movement upon the rails.

Devices of this character are employed for coupling pulley-blocks of various kinds, such 60 as shown at 24, to the rails for use in wrecking operations to assist in rerailing cars, locomotives, and in drawing wrecked or other material toward the rails to bring it within reach of derricks or other hoisting apparatus, 65 and the simple device herein shown and described is a very convenient structure for this purpose.

The device can be easily handled by one man and quickly placed in position or removed when required and clamped to the rail at any required locality.

Having thus described the invention, what is claimed is—

1. A railway-rail anchor comprising two 75 plates for embracing the rail from opposite sides and extending above the same and provided with centrally-disposed transverse apertures in said upwardly-extended portions, the lower portions of said plates conforming 80 to the ball, vertical web and tie flange of the rail, and transverse tie-bolts connecting the plates near the ends and above the rail.

2. A railway-rail anchor comprising two 85 plates for embracing the rail from opposite sides and extending above the same and provided with centrally-disposed transverse apertures in said upwardly-extended portions, the lower portions of said plates conforming 90 to the ball, vertical web and tie-flange of the rail, transverse tie-bolts connecting the plates near the ends and above the rail, and an endless link engaging said transverse apertures.

In testimony that I claim the foregoing as my own I have hereto affixed my signature 95 in the presence of two witnesses.

GEO. F. FIELDS.
